Primary Examiner—Louis S. Zarfas*Assistant Examiner*—Monica A. Weingart*Attorney, Agent, or Firm*—Kellie Muffoletto Ulrich[57] **CLAIM**

I claim the ornamental design for universal firearm device and accessory mount, as shown.

DESCRIPTION

FIG. 1 is a perspective view of a universal firearm device and accessory mount showing my new design;

FIG. 2 is a side elevation view of the left side of FIG. 1; FIG. 3 is a side elevation view being the side opposite to that shown in FIG. 2;

FIG. 4 is a plan view of the front face of my new design;

FIG. 5 is a plan view of the back face of my new design;

FIG. 6 is a bottom plan view of my new design;

FIG. 7 is a top plan view of my new design;

FIG. 8 is an exploded view showing the four components of my new design;

FIG. 9 is a side elevation view of the inner side of the first component of my new design;

FIG. 10 is a side elevation view of the inner side of the fourth component of my new design;

FIG. 11 is a side elevation view of the left side of the second component of my new design;

FIG. 12 is a side elevation view of the right side of the second component of my new design;

FIG. 13 is a side elevation view of the right side of the third component of my new design; and,

FIG. 14 is a side elevation view of the left side of the third component of my new design.
